BUSHING FOR AUTOMOBILE DOOR CURTAIN RODS

Filed Aug. 14, 1925

FIG. 1.

FIG. 2.

FIG. 5.

FIG. 3.

FIG. 4.

FIG. 6.

INVENTOR:
GEORGE E. BISHOP

By
George W. Saywell
ATTORNEY.

UNITED STATES PATENT OFFICE.

GEORGE E. BISHOP, OF CLEVELAND, OHIO.

BUSHING FOR AUTOMOBILE DOOR-CURTAIN RODS.

Application filed August 14, 1925. Serial No. 50,288.

My invention relates to bushings and particularly to a device of this character adapted to be secured to an automobile door and to receive the supporting end of a rod upon which is mounted and carried an automobile side curtain. More particularly, the invention relates to improvements in a bushing which is formed with means for preventing the turning of the supporting rod in the bushing, specific improved means being also provided for securely locking the bushing itself in the recess formed in the door.

The annexed drawing and the following description set forth in detail certain means embodying my invention, such disclosed means constituting, however, but two of the various forms in which the principle of the invention may be applied.

In said annexed drawing:

20 Figure 1 represents an inside elevation of fragmentary portions of an automobile body and door and a fragmentary elevation of a door curtain rod whose supporting end is mounted in one of my improved bushings 25 secured in a suitable door recess.

Figure 2 is a vertical section, taken in the plane indicated by the line II—II, Figure 1, the supporting rod being omitted;

30 Figure 3 is a side elevation of one form of my improved bushing;

Figure 4 is a front elevation of a slightly modified form; and

Figures 5 and 6 are horizontal sections taken, respectively, in the planes indicated by 35 the lines V—V and VI—VI, Figure 3.

Referring to the annexed drawing in which the same elements are indicated respectively by the same ordinals in the several figures, I indicate by the ordinal 1 a portion of an 40 automobile body having a usual side door 2 upon which is mounted by means of a rod 3 any suitable form of side enclosure or door curtain (not shown), adapted to travel out and in with the door 2 as the latter is opened 45 and shut and adapted to form satisfactory joints with the adjacent side closures and the top when the door is closed. The lower end of this supporting rod 3 is mounted in the top of my improved bushing 5 which in turn is secured to the door 2 and, preferably, 50 is secured in a suitable vertical recess 4 formed in the body of the door 2.

The bushing 5 is formed in any desired manner so as to prevent the turning of the rod 3 therein. In the form of bushing herein shown, the same presents intermediate its

ends an outline angular in cross-section corresponding to that of the adjacently enclosed section of the rod 3, the latter, in the form herein shown, being formed with two flat 60 sides 7 at its lower end adapted to register with plain inner walls 13 of the bushing 5. The bushing 5 herein shown is also shaped so as to present inner bushing shoulders 8 intermediate the upper portion of the bushing and the central angular portion thereof. The upper portion 16 of the bushing shown is circular in cross-section so as to receive an upper cylindrical portion 15 of the supporting end of the rod 3, this cylindrical portion 15 of the rod 3 resting upon the bushing shoulders 8 so that thereby the entry of the rod 3 into the bushing 5 is limited. The bushing 5 is seated in a suitable door recess 4 and for purposes of illustration I have 75 shown the door recess 4 circular in cross-section corresponding to the section 16 of the bushing 5, said section 16 of the bushing 5 having an upper end flange or cap 6. I form the bushing 5 with a lower extension 14 below 80 the angular wall portion 13 and below the bottom end of the supporting rod section 7.

The particular improvements of this invention consist in securing the wall 9 of this lower bushing extension 14 to the wall of 85 the door recess 4 so as securely to lock the bushing in the door recess. The construction is particularly serviceable in obviating the turning of the bushing in the door recess when inserting the curtain-carrying rod. 90 In the accompanying drawing the particular form of lower bushing extension 14 comprises an integral cylindrical extension corresponding to the upper cylindrical portion 16 of the bushing 5. The means which I 95 have provided for securely locking this bushing extension 14 in the door recess 4 comprises a screw 10 which is formed with a long thread which reaches across the part 14 of the bushing, this screw 10 being inserted from any suitable side of the door. The screw 10 will worm its way through the bushing walls 9, threading the latter so that they virtually become nuts, whereby the bushing is securely locked to the wall of the 100 door recess 4. By reason of the length of the thread formed upon the screw 10, it reaches the entire distance across the bushing 5, as plainly shown in Figure 2, and after the screw commences to worm its way through 110 the far wall of the bushing, the near wall is tightly drawn up against the wall of the

recess 4, tending to pull the far wall away from the wall of the recess adjacent to it, and actually spacing said far wall of the bushing from the adjacent wall of the recess, 5 if the bushing is a loose fit within the recess. This results in an effective locking of the bushing and not merely a more or less insecure fastening which is apt to hold the bushing very loosely. Even if the lower end 10 of the bushing 5 happens to be a loose fit in the door recess 4, still this section 14 is drawn rigidly up against the wall of the door recess 4 by the action of the screw 10 worming its way through the bushing wall 9. It is immaterial whether the bushing portion 14, before the bushing 5 is driven into the door recess 4, is provided with a hole, or pair of holes to receive the forward end of the screw 10. I have shown the form of bushing in Figure 3 15 provided with such holes 11 and the form of bushing in Figure 4 not so provided. In either event, the screw 10 will worm its way through the bushing walls 9 so as virtually to make nuts of the latter. The holes 11 have 20 a diameter about equal to the diameter of the screw 10 at the root of thread only, so that the threads of the latter work their way through the material of the bushing wall. The long thread of the screw 10 not only locks 25 the bushing in the door recess, as hereinbefore explained, but the screw 10 itself is securely locked, particularly when the ordinarily thin material used for bushings is intersected by the screw threads. In order to obtain perfect 30 registry of the hole drilled in the door 2 with the holes 11 formed in the bushing walls 9, I prefer to form the holes 11 at the same time that the hole is drilled in the door 2. This drilling is done by the aid of a suitable jig 35 after the bushing 5 has been driven into the door recess 4. Although the screw 10 may 40 be inserted from any suitable side of the door

2, I have illustrated in the accompanying drawing the insertion of the same from the inner face of the door 2, the same extending 45 across the bushing portion 14 and taking into the wood of the door 2 adjacent the outer face of the latter.

The bushing 5 may be made from any suitably soft material permitting the screw 50 10 to worm its way therethrough and may be formed in various ways. Suitable cylindrical tubing may be utilized, or the bushing may be cast, or formed in other ways such as 55 properly turning up a flat blank.

In the particular application of my invention shown in Figure 1, the bushing 5 is secured to the door 2 adjacent the closing edge of the latter, the supporting rod 3 being formed with an offset 12. This offset 12 provides means for mounting the rod 3 upon the door 2 and still allowing for the insertion of the upper end of the rod in the edge of the door curtain so as to provide a suitable lapping joint between the door curtain and the 60 adjacent side closure.

What I claim is:

The combination with an automobile body section formed with a bushing recess; of a bushing seated in said recess and formed with 70 a hole for receiving the supporting end of a curtain-carrying rod, means for preventing the turning of the rod in the bushing, and a screw formed with a long thread positioned in said automobile body, and extending 75 across the bushing below the rod end and into the body material upon the opposite side, said screw having wormed its way through the bushing walls to lock the bushing in said body recess when it was positioned in said 80 automobile body, whereby the bushing is prevented from turning in the body recess.

Signed by me this 8th day of July, 1925.

GEORGE E. BISHOP.
